INSULATING SIDING PANEL FOR BUILDINGS

Felix Steckl, Malapardis Road, Morris Plains, N.J.,
and Edgar R. Wengenroth, Jr., 166 Wyckoff Ave.,
Wyckoff, N.J.

Filed June 21, 1957, Ser. No. 46,677

Term of patent 14 years

(Cl. D68—1)

FIG. 1.

FIG. 2.

FIG. 3.

FIG. 4.

FIG. 1 is a top plan view of an insulating siding panel for buildings, showing our new design; and

FIG. 2 is a view taken along the lower edge of the panel shown at FIG. 1; and

FIG. 3 is a view taken along the horizontal edge of a panel shown at FIG. 1; and

FIG. 4 is an enlarged cross-sectional view taken at the lines 4-4 of FIG. 1.

We claim:

The ornamental design for an insulating siding panel for buildings, as shown.
